UNITED STATES PATENT OFFICE.

OTTO KAMPFE, OF NEW YORK, N. Y.

CANDLE-HOLDER.

1,035,711.

Specification of Letters Patent. Patented Aug. 13, 1912.

Application filed September 30, 1911. Serial No. 652,084.

To all whom it may concern:

Be it known that I, OTTO KAMPFE, a citizen of the United States, residing in the borough of Brooklyn, county of Kings, city 5 and State of New York, have invented an Improvement in Candle-Holders, of which the following is a specification.

This invention relates to candle holders, and the object thereof is the provision of an 10 article of this or like character, which is of simple construction and is positive in action.

In carrying out my invention, I preferably employ a plurality of swinging jaws 15 adapted to engage and hold the candle or other article to be supported and secured in position, a member in which the said jaws are pivotally mounted so as to swing, a member co-acting with the aforesaid member and with the said swinging jaws so that by a relative movement between the said members the swinging jaws are moved to position to clamp and secure a candle or other article in place.

25 In the drawing Figure 1 is an elevation and partial section of a candle holder illustrating the features of my present invention. Fig. 2 is a plan view with the candle removed. Fig. 3 is a sectional plan on line 30 $\alpha\alpha$ Fig. 1, and Fig. 4 is an elevation illustrating a modified form of the invention.

Referring to the drawing, my improved candle holder preferably comprises a base 10 which may be made as illustrated in Fig. 35 1, or otherwise, and to which base a standard 11 is secured. As illustrated, this standard 11 is preferably tubular and at its upper end is interiorly screw-threaded, as shown at 12. At its upper extremity the standard 40 11 is also provided with a flange 13, preferably extending outwardly therefrom and at right-angles thereto.

Together with the base and standard I 45 employ a head member which preferably comprises a shank 14 which is cylindrical and exteriorly screw-threaded to enter the upper portion of the standard 11 and to engage the screw-threaded interior thereof so that by turning the shank 14 there is a relative longitudinal movement between the shank and the standard 11. The upper or outer end of the shank 14 is reduced in cross-section, as indicated at 15, and fitting 50 over this reduced end 15 of the shank 14 I 55 prefer to employ a pair of plates 16 and 17 which are preferably circular in outline and

each provided centrally with an opening 18 to receive the reduced end 15 of the shank 14. The plate 16 in its upper surface and adjacent to its periphery, is provided with a circular recess 19, and the plate 17 in its inner surface is similarly provided with a recess 20, so that when these plates 16 and 17 are placed together enjoining the parts, the recesses 19 and 20 are in juxtaposition. The 60 edges of the plates 16 and 17 in equally spaced positions are both provided with notches 21. I also employ a plurality of swinging jaw members, each one of which is indicated by 22. Each swinging jaw member is provided approximately centrally with trunnions 24, which when the swinging jaw is passed within one of the notches 21 in the edges of the plates 16 and 17, lies within the space provided for by the recesses 19 and 20, it being understood that as many of these swinging jaw members as may be desired may be employed, and in any case there are provided a corresponding 65 number of the notches 21, each to receive 70 one of the swinging jaw members, and while I have illustrated three of these swinging jaw members, I do not limit myself to the use of this number. On the outer or upper surface of the plate 17 I provide a disk 26, 85 and passing through the same and into the reduced end of the shank 14 is a screw 27, by means of which the disk, the plates and the shank are secured together.

In order to assist in assembling the parts, 90 particularly in bringing the notches 21 in one plate into alignment with the notches in the other plate, I may employ a pin 28, secured in the shank 14, projecting longitudinally therefrom and passing into and 95 through the plates 16 and 17 in the recess therein, forming part of the opening 18, into which the reduced end of the shank 14 is received.

As illustrated in Fig. 1, the upper end of 100 each of the swinging jaw members may be rounded and so shaped as to terminate in a point adapted to engage the candle 29 to secure the same in position, and the lower end 25 of each of the swinging jaw members, 105 or that portion of each of these members below the pivotal point are engaged at the inner edge by the outer surface of the flange 13.

It will now be apparent that by turning 110 the head member in the upper end of the standard, the distance between the engag-

ing parts of the upper ends of the swinging jaws may be varied to receive same and hold in position a candle or similar article of any diameter within the limits to which 5 the swinging jaws may open and close. It will also be understood that while I have illustrated my invention as applicable to a candle stick, that the same may be used for various purposes, as for example, in Christ- 10 mas-tree ornaments, mops and other like articles.

In some instances it may not be desirable to have the candle engaging ends of the swinging jaws pointed at their extremities, 15 and in such instances it will be apparent, as illustrated in Fig. 4, that the swinging jaws may be reversed in position, so that, as shown in this figure, the rounded portions of the engaging ends of the jaws will come into 20 contact with the candle, or other device, to grip and hold the same in position.

I claim as my invention:

1. A candle holder comprising a base and tubular standard at its upper end internally threaded and having an outwardly extending flange, a shank exteriorly threaded and screwing into said standard, a pair of plates, a disk and a central screw for removably holding said plates to the shank, and said plates notched at spaced intervals, 45 means for bringing said plates into coincidence, a plurality of swinging jaw members and means for pivotally connecting the same in said notches to said plates, whereby the jaw members are actuated by the afore- 50 said flange.

plates notched at spaced intervals, a plurality of swinging jaw members, each having a cam surface on the inner edge below, but adjacent to the pivot and bearing upon the said outwardly extending flange, and means for pivotally connecting the same in said notches to said plates, whereby the 35 jaw members are actuated by the aforesaid flange.

2. A candle holder comprising a base and tubular standard at its upper end internally threaded and having an outwardly extending flange, a shank exteriorly threaded and screwing into the said standard, a pair of plates, a disk and a central screw for removably holding said plates to the shank, and said plates notched at spaced intervals, 40 means for bringing said plates into coincidence, a plurality of swinging jaw members and means for pivotally connecting the same in said notches to said plates, whereby the 45 jaw members are actuated by the afore- 50 said flange.

Signed by me this 26th day of Sept. 1911.

OTTO KAMPFE.
